CARRIER

Graham P. Crutchfield, Albany, Texas

Application June 28, 1932. Serial No. 619,790

2 Claims. (Cl. 368—7)

My invention relates to a carrier for supporting reciprocating steel rods or cables, termed pull or shackle rods, employed in the multiple pumping of oil wells, but it is to be understood 5 that a carrier, in accordance with my invention is also designed for use in any connection for which it is found applicable.

As is well known in multiple pumping of oil wells, each pull rod is mounted in and slides back 10 and forth in spaced supports termed carriers. This is a source of serious friction and necessitates the constant lubrication of the supports requiring a large amount of labor. The lubricant used is a source of another serious difficulty, as rain washes it off; dust fills it full of grit and cold weather hardens it. These adverse weather conditions frequently increase friction on the supports to such a point that the power can no longer pump the usual number 15 of wells, and some of the wells have to be disconnected until the supports can be supplied with fresh lubricant.

To overcome the several objectionable features referred to is the aim of my invention which is 20 attained by providing, in a manner as hereinafter set forth, a carrier which will materially reduce friction; capable of being employed without lubrication; having no sliding contact with the rod; of full roller bearing type, unaffected by 25 weather conditions; having no lubricant thereon to harden or to be washed off; and to attain these ends in a strong, durable, compact, thoroughly efficient, simple and inexpensive structure.

To the above ends essentially, and to others which may hereinafter appear, my invention consists of such parts and such combination of parts which fall within the scope of the invention as claimed.

40 In the drawing:

Figure 1 is a side elevation of the carrier showing it in supporting position with respect to a pull rod.

Figure 2 is an elevation of the carrier looking 45 towards an edge thereof.

Figure 3 is a vertical sectional view of the carrier.

The carrier includes a roller having a grooved edge and its body part can be composite or of 50 one-piece. It may be set up with a renewable wear face of any desirable material. By way of example, the roller is shown as having a one-piece body part constructed of any suitable metallic material and of the desired thickness and 55 diameter. The roller generally indicated at 1

includes a body part 2 having an axial opening 3. The edge 4 of body part 2 has an endless groove 5 of semi-oval cross section.

Extending through the opening 3, as well as being fixed to the wall thereof is a rolling pin 60 6 formed of a central portion 7, a pair of curved tapered intermediate portions 8, 9 and a pair of end portions 10, 11 of circular cross section disposed in alignment with the longitudinal median of portion 7. The portions 10, 11 are of 65 like and uniform diameter throughout and the diameter of each is materially less than that of portions 7. The smallest ends of the portions 8, 9 merge into and are flush with the inner ends of the portions 10, 11 respectively. The 70 largest ends of portions 8, 9 merge into and are flush with the ends of portion 7. The length of portion 7 is greater than that of either portion 10, 11. The portions 8, 9 are of less length than portions 10, 11, the latter being of equal length. 75 The roller 1 is disposed centrally of portion 7, and the latter extends from each side face of body part 2.

The carrier also includes a pair of parallel spaced track elements 12, 13 for the end portions 80 10, 11 respectively of the rolling pin 6. The track elements are mounted in a support in a manner to permit of the manual adjustment thereof, that is to say for intermittently rotating them relative to their support to present new wearing faces for 85 the end portions of the pin 6. Each track element comprises a track or rail forming part 14 of circular cross section provided at one end with peripheral threads 15 and at its other end with a head 16. Carried by portion 15 is a nut 17 which 90 associates with head 16 for detachably anchoring the element to the support, the latter being common to both track elements. The pin 6 reciprocates upon elements 12, 13 simultaneously 95 with the rolling thereof.

The support for the track elements is generally indicated at 18 and it includes a rectangular plate 19 having each end thereof provided with a pair of spaced vertical oblong arms having their outer lengthwise edges flush with the side edges 100 of plate 19 and their outer side faces flush with the end edges of the latter. The arms at one end are indicated 20, 21 and those at the other end at 22, 23. The arm 20 is arranged in parallel spaced relation to the arm 22 and the arm 21 is arranged in parallel spaced relation to arm 23. Each of said arms is of rectangular cross section. The lower ends of the arms are disposed transversely with respect to plate 19. The inner lengthwise edges of the arms 20, 22 are arranged 105 110

in parallel spaced relation with respect to the inner lengthwise edges of the arms 21, 23 respectively. Each of said arms is formed with a pair of spaced superposed aligning openings 24, 25 in 5 the upper portion thereof. The openings in arm 20 align with the openings in arm 22. The openings in arm 21 align with the openings in arm 23. The arm 20 is connected with the arm 22 by a vertically disposed web 26 which is integral 10 with plate 19 and arms 20, 22, as well as having its inner face flush with the inner lengthwise edges of the arms. The arm 21 is connected with the arm 23 by a vertically disposed web 27 which is integral with plate 19 and arms 21, 23, as 15 well as having its inner face flush with the inner lengthwise edges of the arms. Each web is of a thickness materially less than the width of an arm. Formed integrally with the lower face of plate 19 is a depending socket forming member 20 28 for anchoring element 18 or for securing the latter to a standard or other supporting device. The member 28 includes a tubular body part 29 having opposed lengthwise cutouts 30 opening at the lower end of body part 29, and the latter 25 is also formed with opposed lengthwise extending slots 31. The lower end of body part 29 is laterally enlarged as at 32 and is formed with a beveled bottom edge 33.

The openings 25 are arranged above the webs 30 26, 27. Normally each track element is arranged to extend through a pair of aligning openings 25 and revolvably support the rolling pin 6 during the reciprocating of the latter.

A pull rod 34 is shown as supported in the 35 groove 5 of roller 1. The aligning openings 24 are to be used for receiving the track elements when it is desired to hold down on rod 34, the latter in this case would be placed under roller 1.

A pull rod or other object resting against roller 40 1 may have a reciprocating motion substantially greater than the reciprocating motion of the pin which supports the roller, and therefore the construction as referred to provides a full roller bearing guide and support of simple and compact 45 form for any object having a reciprocating motion.

The rolling pin 6 is so shaped that the roller is forced to move in a plane parallel to the tracks or rails. The intermediate portions 8, 9 of pin 6 provide the action just referred to. The arms act as stops to limit the travel of pin 6 in opposite directions. The roller, pin and track elements are separately replaceable. The arms and plate of the support 18 provide a pair of spaced opposed reduced yokes for removably supporting the track elements.

What I claim is:

1. In a carrier, a horizontally disposed supporting plate, two spaced pairs of vertical arms, the arms of each pair being arranged in parallel spaced relation and integral at their lower ends with the upper face of said plate, the arms of each pair being free of connection to each other at their upper ends and each provided intermediate its ends with an opening, the openings in each pair of arms arranged in parallelism, and a removable track forming element mounted in the openings of the arms of each pair for bridging the space between the arms, said elements for supporting a reciprocatory rolling unit and arranged in parallel spaced relation.

2. In a carrier, a horizontally disposed supporting plate, two spaced pairs of vertical arms, the arms of each pair being arranged in parallel spaced relation and integral at their lower ends with the upper face of said plate, the arms of each pair being free of connection to each other at their upper ends and each provided intermediate its ends with an opening, the openings in each pair of arms arranged in parallelism, a removable track forming element mounted in the 105 openings of the arms of each pair for bridging the space between the arms, said elements being of circular cross section and arranged in parallel spaced relation, a reciprocatory rolling pin having an intermediate portion confined between 110 and formed with reduced end terminal portions traveling upon said elements, and a roller provided with an axial opening for the passage of the pin, said roller arranged between said pairs of arms and bodily carried with the pin.

GRAHAM P. CRUTCHFIELD.
